CARBURETOR RAM AIR SCOOP

Delbert A. Cody, Dallas, Tex.

Application April 5, 1957, Serial No. 45,601

Term of patent 14 years

(Cl. D77—1)

Fig. 1 is a top perspective view of the carburetor ram scoop embodying my new design.

Fig. 2 is a right side perspective view.

Fig. 3 is a left side perspective view.

The undisclosed bottom portions of the air scoop are substantially plain.

I claim:

The ornamental design for a carburetor ram air scoop, as shown and described.
